UNITED STATES PATENT OFFICE.

LAWRENCE J. HESS, OF COITSVILLE TOWNSHIP, MAHONING COUNTY, AND MERRILL G. BENJAMIN, OF LAKEWOOD, OHIO, ASSIGNORS TO THE BENJAMIN ENGINEERING COMPANY, OF CLEVELAND, OHIO, A CORPORATION OF OHIO.

COMBUSTION CONTROL.

Application filed April 22, 1921. Serial No. 463,675.

To all whom it may concern:

Be it known that we, LAWRENCE J. HESS, residing in the township of Coitsville, county of Mahoning, and State of Ohio, and **5** MERRILL G. BENJAMIN, residing at Lakewood, county of Cuyahoga, and State of Ohio, have invented a new and useful Improvement in Combustion Control, of which the following is a full, clear, and exact description.

10 This application is a continuation in part of our copending application for furnace control, Serial No. 292,954, filed April 26, 1919.

15 The present invention relates to combustion control and more particularly to means for correlating the air and fuel supplies for furnaces to maintain the proper furnace regulation, together with the most economical **20** combustion at varying rates of combustion.

The present invention may be applied to the combustion control in various types of furnaces, such, for example, as steam boiler furnaces, gas producers or the like, in which

25 it is desired to have an automatic regulation combined with automatic correlation of the air and fuel supplies. The term "furnace" is intended to define broadly any device which is supplied with fuel and air and in

30 which combustion takes place. The fuel may be solid fuel, for example coal or coke either in lump, pulverized or powdered form, or may be liquid or gaseous fuel. The combustion is controlled in accordance with

35 some function of the furnace or furnaces. For example, in the case of steam boiler furnaces the combustion will be controlled in accordance with the load carried by the boiler, or the total load on the station or battery

40 of boilers, the object being to regulate the combustion to meet the boiler load requirements. In the case of steam boilers, the function which corresponds to the load may be the pressure variation in the boilers or in

45 the steam supply header, or may be the flow of steam through the header. In the case of gas producers it may be the pressure of the gas in the main or the flow of gas through the main. In other words, the ex-

50 pression "function of a furnace" or "function of a battery of furnaces" as used in this application is intended to include any of the

indicia of variations in the performance of a furnace or battery of furnaces.

The present invention will be described **55** with particular reference to its embodiment in the control of steam boiler furnaces. It is to be understood, however, that it may be embodied in other types of furnaces.

For the best automatic control of steam **60** boiler furnaces certain objects should be attained. The air and fuel supply should be properly correlated for the most advantageous combustion at the various rates of combustion over which the boiler furnace is to **65** be operated. In the case of a battery of boilers the load should be equalized among all of the units operating, each furnace being supplied with the same or the properly correlated amount of fuel and air so that **70** each boiler carries its proportion of the total load. The proper regulation of the combustion will result in the maintaining of substantially uniform steam pressure over **75** the various boiler ratings.

The following considerations show the necessity of meeting the above requirements if a proper automatic control is to be obtained. For every rating of a boiler there exists a certain relation between the fuel bed thickness, the fuel feed and the quantity of air supplied, which results in the highest efficiency. Knowing this and the characteristics of the boiler furnace being used, we are able to approximate these conditions **80** automatically throughout the entire range of operation from the minimum to the maximum boiler rating. In a modern underfeed stoker, for instance, the grate area is fixed and coal is burned over its entire surface and **85** at varying rates to carry the varying loads imposed upon the boiler. It is possible to maintain a constant fuel bed thickness and to accommodate the varying loads by burning the fuel at varying rates of combustion. **90** It is also possible to vary the fuel bed thickness and also its rate of combustion and carry the same variable load. The method which results in the most efficient operation of the particular furnace is employed. **95**

For efficient operation the load must be equalized among all of the boilers in operation. If all of the boilers operating can be depended upon to carry their proper **100**

share of the load, especially during peak loads on the station, fewer boilers are necessary than under common practice which requires that sufficient boilers be carried on the line so that there will be at all times boiler capacity enough connected to carry peak loads even when some boilers are operating at a much lower capacity due to furnace conditions beyond the momentary control of the fireman. The first cost of the station installation may be reduced if the regulation insures an equalization of the load over all of the boilers. It is well known that boilers operated continuously at moderate ratings show better efficiency than boilers operating with varying load from low to very high. The life of the furnace brick work and parts is greater under the conditions of constant load than otherwise. By automatically equalizing the load on all of the boilers, the variations in ratings at which the individual boilers are operated is reduced to the actual variation in the station load. By the system of combustion control herein described, we are enabled to equalize the load among all of the units operating, to secure the most advantageous combustion at the various boiler ratings and to maintain a substantially uniform steam pressure.

In the drawings which illustrate the preferred embodiment of the invention as applied to the control of a battery of steam boilers;

35 Figure 1 is a diagrammatic view of the regulating system; and

Figures 2 to 13, inclusive, are curves illustrating certain conditions and calculations employed in correlating and proportioning 40 the various parts of the system.

In the illustrated embodiment of the invention, two units of a battery of steam boilers are indicated generally by reference numerals 1 and 2. Ordinarily a considerable larger number of units are employed in a battery but two units only are shown for the purpose of illustration. Each unit comprises a steam boiler 3 and its furnace 4. The boilers are shown as provided with 50 economizers 5. The furnaces are fed by power operated stokers 6 driven by electric stoker motors 7. The stokers may be of any suitable form such, for example, as under-feed or chain gate stokers.

55 The air supply or draft is controlled by forced and induced draft fans 8 and 9, respectively. The forced and induced draft fans are driven by electric fan motors 10 and 11, respectively. While it is preferred, and particularly in cases where an economizer is used, to employ induced draft fans as well as forced draft fans, a chimney draft may be employed, if desired, in which case the induced draft will be controlled by 60 individual dampers in the uptake flues of

the several furnaces, such dampers being preferably controlled in accordance with the pressure of the gases in the combustion chamber or passes of the boiler so that the dampers will open in accordance with the air supplied by the forced draft fans, while maintaining the desired pressure of the gases over the fire or in the boiler passes. In such cases the regulation of the air supply in accordance with the load will be controlled by the forced draft fans. 75

The armatures 12 of the stoker motors 7, the armatures 13 of the forced draft fan motors 10 and the armatures 14 of the induced draft fan motors 11 are supplied with current from constant voltage direct current feeder main 15. The speeds of the several motors 7, 10 and 11 are regulated by the current supplied to their respective shunt fields 16, 17 and 18. The field currents for such shunt fields are supplied by the variable speed, variable voltage generators 19, 20 and 21 of a variable speed motor generator set indicated generally by reference numeral 22. The motor generator set is driven by a motor 23, the speed of which is controlled in accordance with the steam pressure in the main steam header 24 of the battery. The armature 25 of the motor 23 is supplied with a constant voltage current from the constant voltage direct current feeder mains 15. The shunt field 26 of the motor also receives its current from the feeder mains 15. The current in the shunt field 26 of this motor is varied to vary the speed of the motor by means of a rheostat 27 having a movable contact 28 controlled by a steam pressure regulator 29 connected by means of a pipe 30 to the main steam header 24. The steam pressure regulator 29 is a device well known in this art and it is therefore not illustrated in detail. The well known Mason regulator is preferably employed although other makes of regulators may be used. The regulator 29 has 105 an arm 31 which assumes various positions in accordance with the steam pressure. The regulator is so compensated that the arm 31 has a step-by-step movement, assuming a definite position for any particular steam 115 pressure throughout its range of operation. As illustrated in the drawings, the arm 31 is shown as vertically movable, falling with a decrease in steam pressure and rising with an increase in steam pressure. When the 120 stem pressure decreases, the arm 31 and the movable rheostat contact 28 descend cutting out resistance in the rheostat 27, thereby increasing the strength of the motor field 26 and decreasing the speed of the motor generator set. When the steam pressure increases the reverse operation takes place and the speed of the motor generator set is increased. Since the contact point 28 is 125 moved with a step-by-step movement along 130

- the rheostat 27, the speed of the motor generator is regulated in accordance with the steam pressure. The exact relation of the motor generator speed to the steam pressure will hereinafter be described in greater detail. A hand operated rheostat 32 is interposed in the leads on the motor field 26 so that the speed can be adjusted manually in accordance with particular furnace-operating conditions. The hand operated rheostat 32 is not depended upon for regulation in accordance with the variations in the load, but is rather in the nature of a permanent adjustment, which may be set once for all or may be readjusted occasionally upon variation in the character of the fuel, etc.
- The armature 40 of the generator 19 is connected to leads 41 from which is taken the exciting current for the fields 16 of the stoker motors 7 of the several furnaces. The shunt field 42 of the generator 19 is connected across the constant voltage supply mains 15. A manually adjustable rheostat 43 is inserted in the field circuit. The voltage of the current supplied by the generator 19 varies in accordance with the speed of the motor generator set 22 which is varied in accordance with the demand for steam as is shown by the steam pressure regulator 29. When the steam pressure decreases, indicating increased load, the motor generator set decreases in speed, thereby decreasing the voltage supplied by the generator 19 to the fields of the stoker motors and thereby weakening the stoker motor fields and increasing the motor speeds to supply more fuel. The rheostat 43 is not depended upon for adjustment of the stoker motor speeds in accordance with the variations in steam pressure, but is in the nature of a permanent adjustment which may be set once for all or readjusted occasionally when it is necessary to adjust the stoker motors with respect to the draft appliances. Each stoker motor has a manually adjustable rheostat 44 in series with its field. This rheostat allows hand regulation of each stoker motor. This hand regulation is in the nature of a permanent adjustment of the hand rheostat 44 and may be adjusted occasionally to correct any inequalities or differences in conditions between the individual stokers.
- The generator 19 has a series field 45 of such strength that the voltage at any given speed will be maintained constant for variations in the load imposed upon the generator such, for example, as throwing on a different number of stoker motor fields. This renders the relation independent of the load thrown upon the regulating device by a greater or smaller number of units.
- The generator 20 has its armature 50 connected to the leads 51 from which is taken the exciting current for the fields 17 of the forced draft motors 10 of the several furnaces. The field 52 of the generator 20 is connected across the constant voltage feeder mains 15. A manually adjustable rheostat 53 is interposed in the field circuit. This rheostat is in the nature of a permanent adjustment or may be adjusted occasionally when it is desired to adjust the speeds of the forced draft fans as a whole with relation to the other devices. An automatically adjustable rheostat 54 is also included in the circuit of the field 52. The rheostat 54 has a movable contact 55 which is carried on the arm 31 of the steam pressure regulator 29. The action of the rheostat 54 is to modify the variations in voltage of the generator 20 due to the variations in speed of the motor generator set. When the arm 31 of the steam pressure regulator 29 rises, and thereby increases the resistance in the rheostat 27 of the motor generator motor 23 to increase its speed, the same movement throws resistance into the circuit of the field 52 of the generator 50. The effect of increasing the speed of the motor generator set is to increase the voltage of the generator 20, but such tendency to increase the voltage is counteracted in part by the increase in the resistance of the circuit of the generator field 52. In consequence of this, the variations in voltage of the generator 20 upon variations in speed of the motor generator set are not as great as the variation in the voltage of the generator 19, whose variations in voltage are due entirely to the variation in speed of the motor generator set.
- Each forced draft fan motor 10 has a manually adjustable rheostat 56 in series with its field whereby an individual manual adjustment of the speeds of the individual forced draft fans is permitted. Such adjustments are in the nature of permanent or semi-permanent adjustments. The adjustment of one of the rheostats 56 changes the relative speed of the particular fan with relation to the other forced draft fans. Such adjustment does not effect the automatic variations of the speeds of all of the forced draft fans as a system in accordance with the variation in steam pressure through the variable speed of the motor generator set.
- The generator 20 has a series field 57 of such strength that the voltage at any given speed will be maintained constant for variations in the load thrown on such generator, such for example as throwing on the fields of a different number of forced draft fan motors when different numbers of boilers are put into or out of commission.
- The generator 21 has its armature 60 connected with leads 61 from which is taken the current for the shunt fields 18 of the motors 11 for the induced draft fans. The

shunt field 62 of this generator is connected across the constant voltage supply mains 15. A hand rheostat 63 is interposed in the field circuit whereby the speeds of the induced draft fans as a system may be manually adjusted with respect to the forced draft fans and stokers when occasion demands. An automatically regulated rheostat 64 is also included in the circuit of the field 62. This 10 rheostat has a movable contact 65 carried on the arm 31 of the steam pressure regulator 29. The operation of this rheostat is similar to that of the rheostat 54 of the generator 20. It serves to modify the voltage 15 of the generator 21 so that its voltage does not exactly follow the variations in speed of the motor generator set. The rheostats 54 and 64 have their resistance values so selected that the voltages of the 20 generators 20 and 21 will have the proper variations for the different speeds of the motor generator set. The computation of such voltage variations is hereinafter described in detail.

25 Each of the induced fan motors 11 has a manually adjustable rheostat 66 in series with its field. These manually adjustable rheostats provide a means for manually adjusting the speeds of the induced draft fans relative 30 to each other to meet inequalities in the conditions encountered in the individual furnaces. These manual adjustments are in the nature of permanent or semi-permanent adjustments. The regulation of the induced 35 draft fans taken as a system is automatic and responds to various loads on the boilers through the motor generator set which serves as a master regulator for the entire battery.

40 The generator 21 has a series field 67 of such strength that the voltage at any given speed will be maintained constant irrespective of the number of induced draft fan motors whose fields are thrown upon the generator 21.

45 The battery of boilers will ordinarily be operated to meet permanent or semi-permanent variations in load by putting the requisite number of units into commission. 50 The units which are out of commission will ordinarily have their fires banked and the draft and stoker motors will be disconnected. As above pointed out, the generators 19, 20 and 21 of the motor generator set are so designed as to excite the fields of 55 a variable number of fan or stoker motors while maintaining a predetermined voltage on such fields for any particular speed of the motor generator set. The regulation of 60 the furnace in accordance with the steam pressure is thereby rendered independent of the number of units being operated and control apparatus will regulate the steam pressure with the same accuracy independently 65 of the number of units being operated, pro-

vided, of course, a sufficient number of units are being operated to carry the load.

The operation of the apparatus will first be described generally and then the computations for determining the various constants of the systems will be explained.

The steam pressure regulator 29 responds to the variations in the steam pressure. The arm 31 is illustrated as rising with an increase in steam pressure and falling with a decrease in steam pressure. The arm 31 will take different positions for different steam pressures. The regulator is set to travel through a complete stroke for a pre-determined pressure variation. For example, if this pressure variation is taken as ten pounds, the arm 31 will be at its bottom position, when the pressure is five pounds below normal, and will be in its top position when the pressure is five pounds above normal. Since the flow of steam out of a boiler can be anything from zero to maximum at practically the same steam pressure at the outlet, and since there is a definite loss or drop of steam pressure in flowing through a pipe, the connection 30 to the regulator 29 is preferably taken from the main steam header 24 at a point where, at the maximum load on the station, the pressure drop to that point from the boilers is approximately that at which the regulator is set to make a full stroke. Under these conditions, with no load on the station the pressure at the boilers and at this point will be the same, and slightly above normal, whereas, at a maximum load, the pressure at the point where the connection 30 is taken off, will be lower than that at the boilers by approximately the number of pounds required for a full stroke of the pressure 10 regulator 29, for example, ten pounds in the above assumed example. By tapping the connection to the steam pressure regulator as above described, the action of the regulator will follow closely the load on the station.

As the load on the station decreases, the arm 31 of the steam pressure regulator rises thereby increasing the resistance of the rheostat 27 and weakening the field of the motor 11 23 of the motor generator set. This increases the speed of the motor generator thereby increasing the voltages of the generators 19, 20 and 21. These voltage increases in turn increase the field strengths 120 of the stoker and the forced draft fan and the induced draft fan motors, thereby decreasing such motor speeds. Less fuel and air is supplied to the furnaces to compensate for the decreased load on the station. 125 Conversely, if the load on the station increases, the arm 31 of the steam pressure regulator descends cutting resistance out of the rheostat 27 and decreasing the speed of the motor generator set. This in turn de- 130

creases the voltage supplied to the fields of the stoker motors and the fan motors, thereby increasing their speeds and supplying more fuel and more air to the furnaces

5 to carry the increased load on the boilers.

The speeds of all of the individual stoker and fan motors of the units of the battery are controlled through the motor generator electrical system from the single master

10 steam pressure regulator 29 which is in turn controlled by the pressure in the main steam header 24. The rate of combustion over the entire battery will therefore be varied in accordance with the load carried by the

15 entire battery. The variations in speed of the motor generator set causes properly responsive variations in speeds of the motors of all of the units so that the variations in fuel and air supplies for the differ-

20 ent rates of combustion are properly correlated over the entire battery. The motors of each unit have their own adjustable hand rheostats so that any motor may be adjusted relatively to the other motors of its

25 system. By means of such adjustment the load can be very accurately equalized over the several boilers of the entire battery. The change in the speed of the motor generator due to the variations in the load does

30 not effect the equal distribution of the load between the several units, as changes in the speed of the motor generator cause proportionate changes in speed of the motors of all of the units.

35 When the manually adjustable rheostats for the different units are set, the operation of the system is entirely automatic and the hand rheostats will not need to be touched until there is some permanent or semi-per-

40 manent change in the operating conditions. For example, when one boiler is dirty and another freshly cleaned, it may be necessary to adjust the rheostats so as to give somewhat greater speed to the draft fans

45 of the dirty boiler to overcome the greater resistance through its passes. After such adjustment is made, the regulation is thereafter automatic and no further hand adjustment will be necessary until conditions

50 are changed, for example cleaning the dirty boiler and the gradual fouling of the clean boiler.

The system not only equalizes the load over the several units of the battery, but also supplies properly correlated amounts of fuel and air at different rates of combustion, whereby the most efficient burning of the fuel is maintained over the entire boiler ratings from the minimum rating to

60 maximum overload. The constants of the system for such regulation are determined as follows: For the purposes of explanations a number of curves, Figures 2 to 13, inclusive, are presented. It is to be under-

65 stood that these curves are merely diagram-

matic and are used for the purpose of more graphic explanation. They are not intended to be accurately drawn to scale.

A curve of the efficiency of the boiler or boilers to be controlled is obtained. This is ordinarily obtainable from actual tests of the boilers previously installed. A typical curve of this kind is shown in Figure 2 in which the percentage of boiler ratings are indicated by the abscissæ and the percentage of boiler efficiency at the various ratings is indicated by the ordinates. With this curve as a basis, the actual quantity of a coal of known analysis which will be required for the different ratings of the boiler may be computed. Such a curve representing the relation between the quantity of fuel in pounds per hour and the percentage of boiler rating is shown in Figure 3.

From the knowledge of the quantity of fuel which must be supplied per hour at the different boiler ratings, the stoker speeds at the different boiler ratings may be computed. The curve showing the relation of the stoker speeds in revolutions per minute at the different boiler ratings is shown in Figure 4. This curve furnishes the basis upon which the speeds and the speed variations of the stoker motors at different rates of combustion are computed.

From the tests conducted for obtaining the data necessary to plot the curve of Figure 2, the percentage of excess air required to burn the fuel most efficiently at different boiler ratings is determined. The relationship of the excess air to the present boiler ratings is indicated in the curve shown in Figure 5.

The curve shown in Figure 6 is then plotted with the curves 3 and 5 as a basis. This curve shows the quantity of air in pounds per hour which must be delivered to the furnace at different boiler ratings.

The fuel bed thicknesses for the different percentages of boiler ratings are determined for the most efficient combustion and the static pressures under which the forced draft fan must operate at the different percentage boiler ratings is then determined.

A curve showing the pressure in inches of water to be maintained under the fire by the forced draft fan at the different boiler ratings is shown in Figure 7. The curve in

Figure 8 which shows the speed of the forced draft fan at the different boiler ratings is then calculated on the basis of the curves of Figures 6 and 7. This curve furnishes the basis for computing the electrical constants of the forced draft fan motors and their regulating system.

The quantity of burned gases to be removed by the induced draft fan at the different rates of combustion or boiler ratings is then computed. Since the exact quantities of air and fuel supplied to the furnaces

have been fixed, the quantity of the gases of combustion is known. In plotting the curve of Figure 9, allowance must be made for the infiltration of air through the boiler setting and economizer. Such infiltration increases with the boiler rating and may run from about ten per cent at one hundred per cent rating to about twenty per cent at four hundred per cent rating. The curve of Figure 9 is plotted showing the pounds per hour of the gases of combustion to be removed by the induced draft fan at the different boiler ratings.

The curve shown in Figure 10 is plotted from data obtained by tests with the boiler. This curve shows the negative stack pressures in inches of water under which the induced draft fan will operate at the different boiler ratings.

The curve of Figure 11 is next plotted on the basis of Figures 9 and 10. This curve shows the induced draft fan speed in revolutions per minute at the different boiler ratings. In plotting this curve the temperatures of the gases to be handled by the fan are taken into consideration. The temperature of the gases increases with the boiler rating. For example, the gas temperature may increase from 350 degrees Fahrenheit at 100 per cent boiler rating to 600 degrees Fahrenheit at 400 per cent boiler rating. Since the pressures and amounts of air and gas can be determined for the different boiler ratings, fans having the best characteristics for carrying the loads may be selected.

The various fan manufacturers furnish data for the different types of fans upon which data the speeds of the fans, both of the forced and induced drafts, may be accurately computed at the different boiler ratings. The speeds required at the different boiler ratings by the stokers, the forced draft fans and the induced draft fans, together with the loads to be carried at such speeds, being known, electric motors of the proper size and range of speed may be selected. Motors are also selected having the desirable shunt field characteristics to give the proper speed regulation by varying the field voltage applied to the motors. Since the speeds of the stoker, the forced draft fan and the induced draft fan motors at different boiler ratings is known, and since their shunt field characteristics are known, curves may be plotted showing the voltage which must be applied to the shunt field windings of the motors at the different boiler ratings to obtain the proper speed of the stoker, the induced draft fan and the forced draft motors. Typical curves showing this relationship are shown in Figure 12. In the example selected, the stoker motor has the greatest variation in speed over the different boiler ratings, the induced

draft fan the next largest variation and the forced draft fan the least variation. These speed variations are determined very largely by the characteristics of the fan and for fans of some characteristics these relative relationships of the speeds of the stoker and the fans may be different.

Since the voltages which may be applied to the fields of the various motors are known, suitable generators 19, 20 and 21 are selected. The speeds of the generators necessary to supply the voltages required by the curves of Fig. 12 may be then computed. Since the voltage curves for the shunt fields of the stoker, the forced draft fan and the induced draft fan motors have different slopes, and since the generators 19, 20 and 21 are mounted on the same shaft, the necessary voltage regulation cannot in general be attained for all three generators by the speed variation of the motor generator set alone. Therefore, the voltage for one set of the motors, say the stoker motors, is obtained by the speed control of the stoker motors generator 19 and voltage for the fields of the forced draft fans and induced draft fans is regulated by the speed of the motor generator set as modified by the rheostats 54 and 64.

On the basis of the curve of the stoker motor shunt field voltage shown in Figure 12, the curve of Figure 13 is computed. This curve shows the speed in revolutions per minute of the generator 19 at the different boiler ratings. This fixes the speed of the motor generator set 22. From the characteristics of the motor 23 of the motor generator set, the resistance values of the elements of the rheostat 27 may be computed. The steam pressure regulator 29 by means of the movable contact 28 will therefore impart to the motor generator set the correct speeds for the different boiler ratings.

Since the speed of the motor generator set is fixed by the stoker motors and their generator 19, the voltage of the generators supplying the fields of the fan motor must be modified to give the proper variations in the shunt field voltage as shown in Figure 12. With Figure 12 as a basis, the values of the resistance elements of the rheostat 64 of the generator 21 which supplies the field currents for the induced draft fan motors may be computed, so that the proper voltage will be supplied at the various boiler ratings.

Similarly, on the basis of Figure 12, the values of the resistance elements of the rheostat 54 for the generator 20, which supplies the field current for the forced draft fan motors is computed. While, for the accurate proportioning of the air and fuel supplies at different rates of combustion it is necessary in most cases to employ the volt-

age modifying rheostats 54 and 64, these might be dispensed with in case the stoker, or fans and their motors had such characteristics that the curves as shown in Figure 12 were substantially parallel.

From the foregoing description it will be apparent that we have provided for an accurate equalization of the load among the several units of the battery and at all rates 10 of combustion we have also provided for an accurate proportioning of the air and fuel supplies at all rates of combustion. This regulation results in the maximum efficiency of the boilers being operated and the 15 maintenance of a substantially uniform steam pressure at different loads.

While the invention has been particularly described as applied to a battery of steam boilers, it will be understood that it may 20 be readily applied to boiler furnaces employing a liquid other than water as, for example, the recently developed mercury boiler.

While the invention has been described in 25 considerable detail with reference to its illustrated embodiment, it is to be understood that the invention is not limited to such embodiment but may be otherwise embodied both in the regulation of steam boiler furnaces and in the regulation of other types 30 of furnaces.

We claim:

1. The method of operating a battery of furnaces having independent means for each 35 furnace for supplying an element of combustion to the furnace and having an electric motor for operating each of such supply means, which includes supplying current to a winding of each motor and varying such 40 current in accordance with a function of the battery, substantially as described.

2. The method of operating a battery of furnaces having independent means for each furnace for supplying an element of combustion to the furnace and having an electric motor for operating each of such supply means, which includes supplying current to a winding of each motor and varying such current in accordance with a function 45 of the battery, and supplementally controlling the voltage of the current supplied to at least one of the motors to compensate for the individual characteristics of its furnace, substantially as described.

55 3. The method of operating a furnace, which includes supplying fuel and air in a definite ratio at a given furnace load, and varying such ratio with changes in the furnace load, substantially as described.

60 4. The method of operating a battery of furnaces, which includes supplying fuel and air to each furnace in a definite ratio at a given load, and automatically varying such ratio with variations in the load of the battery, substantially as described.

5. The method of operating a battery of furnaces, which includes supplying fuel and air to each furnace in definite proportions at a given load, automatically varying such proportions with variations in the load of 70 the battery, and supplementally varying the fuel-air ratio of a furnace in the battery to compensate for its individual characteristics while leaving it susceptible to said automatic variation, substantially as described. 75

6. The combination with a battery of furnaces, of at least one draft fan for each furnace, electric motors for driving the fans, and means for automatically controlling the speeds of the motors comprising means for 80 supplying to a winding of each motor electric current having its voltage controlled in accordance with a function of the battery, substantially as described.

7. The combination with a battery of furnaces, of fuel supply means for each furnace, electric motors for driving the same, and means for automatically controlling the speeds of the motors comprising means for 85 supplying to a winding of each motor electric current having its voltage controlled in accordance with a function of the battery, substantially as described. 90

8. The combination with a battery of furnaces, of fuel supply means and at least one 95 draft fan for each furnace, electric motors for driving the fuel supply means and fans, and means for automatically controlling the speeds of the motors comprising means for supplying to a winding of each motor electric current having its voltage controlled in accordance with a function of the battery, substantially as described. 100

9. The combination with a battery of furnaces, of air and fuel supplying means, electric driving motors therefor and a common controlling means therefor, comprising generators having their output varied in accordance with a function of the battery, said generators being connected with the air and fuel supplying motors to correspondingly vary their speeds, and means for independently regulating the speed of the individual motors, substantially as described. 105

10. The combination with a battery of 115 furnaces, of air and fuel supplying means, electric driving motors therefor and a common controlling means comprising a plurality of generators having their output varied in accordance with a function of the battery, 120 said generators being connected with the air and fuel supplying motors to control their speeds, substantially as described.

11. The combination with a furnace, of air and fuel supplying means therefor and 125 motors therefor, and controlling means comprising generators connected with the air and fuel supplying motors and adapted to regulate the speeds of the motors in accordance with a function of the furnace to sup- 130

ply proportionate amounts of fuel and air to the furnace at varying rates of combustion, substantially as described.

12. The combination with a battery of furnaces, of air and fuel supplying means for each furnace, an electric driving motor for each of the supply means, and a plurality of generators having their outputs varied in accordance with a function of the battery, one of the generators being connected with the air supply means so as to vary the speed of said motors in accordance with said function of the furnace, another generator being connected with the fuel supply motors and adapted to vary the speeds of said motors in accordance with said function of the furnace, substantially as described.

13. Control apparatus for a battery of furnaces, including fuel supplying means, air supplying means, fuel-supplying control means adapted to control the fuel supplying means for all the furnaces in the battery, air-supplying control means adapted to control the air supplying means for all the furnaces in the battery, means responsive to a function of the battery operatively connected with both the air and fuel supplying control means and adapted to vary the same to increase or decrease the rate of fuel and air supply with varying demands on the battery, and means for varying the effect of variations of the means responsive to the battery function on the fuel and air supplying control means whereby the fuel-air ratio for the entire battery may be varied by such adjustment, substantially as described.

14. Control apparatus for a battery of furnaces, including fuel supplying means, air supplying means, fuel-supplying control means adapted to control the fuel supplying means for all the furnaces in the battery, air-supplying control means adapted to control the air supplying means for all the furnaces in the battery, means responsive to a function of the battery operatively connected with both the air and fuel supplying control means and adapted to vary the same to increase or decrease the rate of fuel and air supply with varying demands on the battery, means for varying the effect of variations of the means responsive to the battery function on the fuel and air supplying control means whereby the fuel-air ratio for the entire battery may be varied by such adjustment, and means for individually adjusting the air and fuel supplying means for any furnace in the battery while leaving such means susceptible to the common battery control, substantially as described.

15. Control apparatus for a battery of furnaces, including fuel supplying means, forced draft means and forced draft regulating means and induced draft means and induced draft regulating means, fuel-supply-

ing control means adapted to control the fuel supplying means for all the furnaces in the battery, forced draft control means adapted to control all the forced draft regulators, induced draft control means adapted to control all the induced draft regulators, means responsive to a function of the battery operatively connected with all of said control means and adapted to vary the same to increase or decrease the rate of fuel and air supply with varying demands on the battery, and means for varying the effect of variations of the means responsive to the battery function on any of said control means, substantially as described.

16. The combination with a battery of furnaces, of air and fuel supplying means, electric driving motors therefor and a common controlling means comprising a motor generator set having its output varied in accordance with a function of the battery, the generators of such set being connected with the air and fuel supplying motors to correspondingly vary their speeds, and means for independently regulating the speed of the individual motors, substantially as described.

17. The combination with a battery of furnaces, of air and fuel supplying means, electric driving motors therefor, and a common controlling means comprising a motor generator set having its output varied in accordance with a function of the battery, the generators of such set being connected with the air and fuel supplying motors to control their speeds, substantially as described.

18. The combination with a battery of furnaces, of air and fuel supplying means, electric driving motors therefor, and a common controlling means therefor comprising a motor generator set having its speed varied in accordance with a function of the battery, the generators of such set being connected with the air and fuel supplying motors to correspondingly vary their speeds, and means for independently regulating the speed of the individual motors, substantially as described.

19. The combination with a battery of furnaces, of air and fuel supplying means, electric driving motors therefor, and a common controlling means comprising a motor generator set having its speed varied in accordance with a function of the battery, the generators of such set being connected with the air and fuel supplying motors to control their speeds, substantially as described.

20. The combination with a furnace, of air and fuel supplying means and motors therefor, and controlling means comprising a motor generator set having its output varied in accordance with a function of the furnace and having generators connected with the air and fuel supplying motors and

so constructed and arranged as to regulate the speeds of the motors in accordance with the said function of the furnace to supply the correct proportionate amounts of air and fuel at the varying rates of combustion, substantially as described.

21. The combination with a furnace, of air and fuel supplying means, and controlling means therefor acting automatically to

10 supply air and fuel in suitable ratio to carry a given load upon the furnace, said means being adapted to vary the fuel-air ratio as the rate of combustion is varied, substantially as described.

15 22. The combination with a battery of furnaces, of air and fuel supplying means for each furnace, electric driving motors therefor, and a controlling means comprising a motor generator set having its output

20 varied in accordance with a function of the furnace, and having generators connected with the air and fuel supplying motors so as to vary the motor speeds in accordance with the output of the motor generator set,

25 and means connected with one of the generators for modifying the voltage impressed by said generator upon its controlled motors, substantially as described.

23. The combination with a battery of 30 furnaces, of air and fuel supplying means for each furnace, electric driving motors therefor, and a controlling means comprising generators having their output varied in accordance with a function of the fur-

35 nace and having such generators connected with the air and fuel supplying motors so as to vary the motor speeds in accordance with the output of the generators, and means connected with one of the generators

40 for modifying the voltage impressed by said generator upon its controlled motors, substantially as described.

24. The combination with a battery of furnaces, of independently driven air supplying and fuel supplying means for each furnace adapted to supply air and fuel to such furnace in definite proportions for a given load, controlling means therefor acting automatically to supply approximately

50 equal amounts of fuel and air to each of the individual furnaces in predetermined proportions, means for supplementally controlling the proportions of air and fuel supplied to any furnace while leaving its air

55 and fuel supplying means susceptible to the centralized controlling means and means for modifying the effect of said control means on the supplying means for one of the elements of combustion for all of the furnaces, substantially as described.

25. Control apparatus for a battery of furnaces, including fuel-supplying means and a stack damper for each of the furnaces, fuel-supplying control means adapted

60 to control the fuel-supplying means for all

the furnaces in the battery, damper control means adapted to control the stack dampers for all the furnaces in the battery, and means responsive to a function of the battery operatively connected with both the control 70 means and adapted to vary the same to increase or decrease the rate of fuel and air supply with varying demands on the battery, substantially as described.

26. Control apparatus for a battery of 75 furnaces, including fuel-supplying means and a stack damper for each of the furnaces, fuel-supplying control means adapted to

control the fuel supplying means for all the furnaces in the battery, damper control 80 means adapted to control the stack dampers for all the furnaces in the battery, means responsive to a function of the battery operatively connected with both the control means and adapted to vary the same to increase or decrease the rate of fuel and air supply with varying demands on the battery, and means for varying the effect of variations of the function-responsive means on at least one of said control means, sub- 85

stantially as described.

27. Control apparatus for a battery of furnaces, including fuel-supplying means and an induced draft fan for each of the furnaces, fuel-supplying control means 90

adapted to control the fuel-supplying means for all the furnaces in the battery, induced draft fan control means adapted to control the induced draft fans for all the furnaces in the battery, and means responsive to a 100 function of the battery operatively connected with both the control means and adapted to vary the same to increase or decrease the rate of fuel and air supply with varying demands on the battery, substantially as 105 described.

28. Control apparatus for a battery of furnaces, including fuel supplying means and an induced draft fan for each of the furnaces, fuel-supplying control means 110

adapted to control the fuel-supplying means for all the furnaces in the battery, induced draft fan control means adapted to control the induced draft fans for all the furnaces in the battery, means responsive to a function of the battery operatively connected with both the control means and adapted to vary the same to increase or decrease the rate of fuel and air supply with varying demands on the battery, and means for 115 varying the effect of variations of the function responsive means on at least one of said control means, substantially as described.

29. The combination with a battery of 120 furnaces, of independently driven fuel and air supplying means for the individual furnaces in the battery, control means actuated in accordance with a function of

125 the battery and effective for controlling 130

all of the supply means, means for modifying the effect of said control means on the supply means for the individual furnaces, and means for modifying the effect 5 of said control means on the supplying means of one of the elements of combustion for all of the furnaces, substantially as described.

30. The combination with a battery of 10 furnaces, of independently driven fuel and air supplying means for the individual furnaces in the battery, control means actuated in accordance with a function of the battery effective for controlling all of the supply 15 means and tending toward the supply of fuel and air to all of the furnaces in a predetermined ratio, means associated with an individual furnace to modify the fuel-air ratio imposed by said control means 20 on such furnace and means for modifying the effect of said control means on the supplying means of one of the elements of combustion for all of the furnaces, substantially as described.

25. 31. The method of operating a battery 30 of furnaces which includes controlling the rate of supply of the elements of combustion to the furnaces in the battery in accordance with a function of the battery and 35 supplementally controlling at least one furnace in the battery to cause a departure from such rate of supply of an element of combustion to such furnace to compensate for its individual characteristics and divide 40 the load uniformly over the furnaces constituting the battery, substantially as described.

32. The method of operating a battery 45 of furnaces each having at least one motor for supplying an element of combustion thereto, which includes varying the speeds of the motors in accordance with a function of the battery and supplementally regulating the speed of at least one motor 50 to compensate for the individual characteristics of its furnace, substantially as described.

33. The combination with a battery of 55 furnaces, of a draft fan for each furnace, an individual driving means for each fan, all of said driving means forming a set, a fuel supplying device for each furnace, an individual driving means for the fuel supplying device of each furnace, all of said 60 driving means forming another set, a control means operating in accordance with a function of the entire battery, and separate connections between said control means and the said several sets of driving means, substantially as described.

34. The combination with a battery of 65 furnaces, of a draft fan for each furnace, an individual driving means for such fan, all of said driving means forming a set, a fuel supplying device for each furnace, an

individual driving means for the fuel supplying device of each furnace, all of said driving means forming another set, a control means operating in accordance with a function of the entire battery, separate 70 connections between said control means and the said several sets of driving means, and supplemental control means for adjusting the fuel-air ratio of each individual furnace while leaving its air and fuel supplying 75 means susceptible to said control means, substantially as described.

35. The combination with a battery of 80 furnaces, of independently driven air-supplying means for each furnace in the battery, an electric driving motor therefor, a common control means actuated in accordance with a function of the battery and effective for controlling all of such motors, and means for modifying the effect of the 85 control means on at least one of the motors, substantially as described.

36. The combination with a battery of 90 furnaces, of independently driven fuel-supplying means for each furnace in the battery, an electric driving motor therefor, a common control means actuated in accordance with a function of the battery and effective for controlling all of such motors, and means for modifying the effect of the 95 common control means on at least one of said motors, substantially as described.

37. The combination with a battery of 100 furnaces, of independently driven fuel and air supplying means for each furnace in the battery, an electric driving motor for each of said supplying means, a common control actuated in accordance with a function of the battery and effective for controlling all of the driving motors, and means for modifying the effect of said control means on at least one of the driving 105 motors, substantially as described.

38. The method of operating a battery 110 of furnaces, which includes supplying an element of combustion to the several furnaces of the battery at a rate for one furnace differing from the rate for another furnace in accordance with the individual characteristics of such furnaces, and varying the 115 rate of supply of such element of combustion for each of the furnaces in the battery in accordance with a function of the battery, substantially as described.

39. The method of operating a battery 120 of furnaces, which includes supplying fuel and air to the several furnaces of the battery at rates for one furnace varying from the rates for another furnace in accordance 125 with the individual characteristics of such furnaces, and varying the rate of supply of fuel and air for each of the furnaces in the battery in accordance with a function of the battery, substantially as described.

40. The method of operating a battery of 130

furnaces, which includes supplying fuel and air to the several furnaces of the battery at rates for one furnace varying from the rates for another furnace in accordance with the individual characteristics of such furnaces, varying the relative rate of fuel and air supply for an individual furnace in the battery, and varying the rate of supply of fuel and air for each furnace in the battery in accordance with a function of the battery, substantially as described.

41. The method of operating a battery of furnaces each having an air supply means and each having a fuel supply means, which includes operating the fuel and air supply means for the several furnaces to supply fuel and air thereto, operating the fuel supplying means for one furnace at a speed differing from that of another furnace, and controlling the operation of all of the fuel and air supply means in accordance with a function of the battery, substantially as described.

42. The method of operating a battery of boiler furnaces, which includes supplying an element of combustion to the several furnaces of the battery at a rate for one furnace differing from the rate for another furnace in accordance with the individual characteristics of such furnaces, and varying the rate of supply of such elements of combustion for each of the furnaces in the battery in accordance with the demand on the battery, substantially as described.

43. The method of operating a battery of boiler furnaces, which includes supplying an element of combustion to the several furnaces of the battery at a rate for one furnace differing from the rate for another furnace in accordance with the individual characteristics of such furnaces, and varying the rate of supply of such element of combustion for each of the furnaces in the battery in accordance with variations in pressure in the battery header, substantially as described.

44. The method of operating a battery of furnaces each having air supply means and each having fuel supply means, which includes operating the fuel and air supply means for the several furnaces to supply fuel and air thereto, controlling a supply means for one of the furnaces to effect the supply of fuel and air thereto in a ratio differing from the fuel-air ratio for another

furnace in the battery, and controlling all of the fuel and air supply means in accordance with a function of the battery, substantially as described.

45. The method of controlling a battery of furnaces having individual supply means for supplying the elements of combustion thereto, which includes substantially simultaneously adjusting a plurality of control means constituting a centralized battery control in accordance with a function of the battery, utilizing the various control means to automatically regulate the supply of the different elements of combustion to all of the furnaces in accordance with such function, and supplementally regulating at least one of the furnaces to compensate for its individual characteristics while leaving it susceptible to the centralized battery control, substantially as described.

46. The method of controlling a battery of furnaces having individual supply means for supplying the elements of combustion thereto, which includes substantially simultaneously adjusting a plurality of control means in accordance with a function of the battery, utilizing the various control means each to automatically regulate the individual supply means for the various elements of combustion to the several furnaces in the battery and relatively adjusting the several control means, substantially as described.

47. The method of controlling a battery of furnaces having individual supply means for supplying the elements of combustion thereto, which includes substantially simultaneously adjusting a plurality of control means in accordance with a function of the battery, utilizing the various control means each to automatically regulate the individual supply means for the various elements of combustion to the several furnaces in the battery, relatively adjusting the several control means, and supplementally regulating the individual supply means to compensate for the characteristics of the furnaces while leaving such supply means susceptible to the centralized battery control, substantially as described.

In testimony whereof, we have hereunto set our hands.

LAWRENCE J. HESS.
MERRILL G. BENJAMIN.
